UNITED STATES PATENT OFFICE.

FREDERICK SQUIRES, OF MARIETTA, OHIO, ASSIGNOR TO WALTER SQUIRES, OF ZANESVILLE, OHIO.

APPARATUS FOR AND METHOD OF RECOVERING OIL AND GAS.

1,249,232.

Specification of Letters Patent.

Patented Dec. 4, 1917.

Application filed June 19, 1917. Serial No. 175,593.

To all whom it may concern:

Be it known that I, FREDERICK SQUIRES, a citizen of the United States, residing at Marietta, in the State of Ohio, have invented 5 certain new and useful Improvements in Apparatus for and Methods of Recovering Oil and Gas, of which the following is a specification, reference being had to the accompanying drawings, forming a part 10 hereof.

This invention relates to an improved method of and apparatus for recovering oil and gas from the earth and will be found especially useful in connection with such recovery where the gasolene is to be removed 15 from the recovered products. In recovering oil and gas from oil bearing strata, in fields where a natural flow is not found, it becomes necessary to introduce a pressure medium 20 into the sands for the purpose of forcing the oil and gas therein to the venting well. It has been proposed to employ either air or natural gas as the pressure medium, but these media are not satisfactory, either be- 25 cause the expense is prohibitive as in the case of natural gas, or because an explosive mixture with the recovered vapor is formed as in the case of air, thereby making this medium unsafe. By the proposed method there 30 is introduced into the oil bearing stratum a deoxidized gas, which has no market value and which, being without free oxygen, may safely be mixed with the hydrocarbons recovered without forming therewith an explosive 35 mixture.

Another phase of the invention is concerned with the association with such a de-oxidized gas of a liquid, such as water, which may be heated, so that these two media of 40 different densities, enter the oil bearing sand together, the water, under pressure, serving to agitate the liquid hydrocarbons, while the deoxidized gas passes along the surface of the liquid hydrocarbon, evaporates and picks up the volatilized gases therefrom. In the development of this improved method of agitating and forcing the hydrocarbon products to the venting well, it is further proposed to heat the water so that the de- 45 oxidized gas, when introduced under pressure, has the heat required for its expansion furnished by the water, thereby preventing the undue chilling of the hydrocarbon products to be recovered. The conditions described approximate most nearly of 50

all known methods those required for the most rapid and complete recovery and volatilization of oil and gas, as will appear in greater detail hereinafter.

The accompanying drawings show apparatus for the practice of the improved method in connection with the removal of gasolene from the recovered products. In 60 the drawings—

Figure 1 shows somewhat schematically 65 complete apparatus associated, respectively, with pressure and venting wells for the recovery of oil and gas from the oil bearing stratum shown and for removing the gasolene from the recovered volatilized products 70 by the absorption method.

Fig. 2 is a view similar generally to Fig. 1, but indicating the removal of gasolene from the recovered volatilized products by the refrigeration method. 75

While, as indicated hereinbefore, the general object of the invention is to improve known methods for recovering oil and gas and is concerned particularly with such methods where the gasolene is to be removed 80 from the recovered volatilized products, it is to be understood that although some of the steps of the method may be used to advantage without the other steps, the apparatus illustrated has been made as complete 85 as possible to indicate permissible variations in the practice of the method. The invention is not to be limited to the precise apparatus disclosed since equivalent elements may be employed and since, as will appear 90

later, some of the elements may be omitted without departing from the spirit of the invention. The two drawings have been made up with a view to illustrating generally the practice of the improved method under different conditions, in one of which the gasolene is to be removed by what is known in the art as the absorption method, while in the other of which the gasolene is removed by the refrigeration method. The particular 100 apparatus for practising these methods, it is to be understood, may also vary through wide ranges. In removing gasolene, however, it is well known that good results are obtained only where the recovered volatilized products are compressed to a high degree. If the mixture thus compressed be explosive, it will be understood that the heat of the compressor or other parts may result in an explosion, and great damage has often 105 110

resulted therefrom. It is for this reason that objection is made in the art to the use of air as a pressure medium for recovering oil and gas from the strata since air mixed with the vapors is apt to form therewith a highly explosive mixture, and this mixture when compressed for the recovery of gasoline, may be exploded as described. Another pressure medium which has been suggested to the art is natural gas. While such a medium satisfies the requirements of safety under compression when associated with the recovered volatilized products, a large part of it is lost by absorption in the oil and its cost is prohibitive as a commercial proposition. The present problem, then, in view of the conditions briefly discussed, is to provide a suitable pressure medium which shall have no commercial value and which may be combined with the recovered products with absolute safety and the resulting mixture be compressed as required. Further, it is necessary that this medium for the best results shall be nonabsorbable by the recovered hydrocarbons and shall not, of itself, be affected physically or chemically during the treatment for the removal of the gasoline.

The improved method in one aspect consists in the recovery of oil and gas from sand strata by the introduction of a deoxidized, nonabsorbable gas, and such gas available commercially in oil fields has been found to be the waste products of combustion of the great number of internal combustion engines used in such fields. In practising the improved method, then, such waste products of combustion from which the free oxygen has been removed, as will be understood, are collected in a reservoir and thence distributed to the pressure wells and introduced into the oil stratum either by direct connection between the reservoir and the pressure wells or through the interposition of a force pump. These waste products of combustion have no commercial value and have been found to be the most desirable medium available for the recovery of oil and gas since, having no free oxygen, they may be combined with the oil and gas without forming an explosive mixture and this mixture may be compressed to any point during the removal of the gasoline without danger of explosion. Further such products of combustion are nonabsorbable by the recovered hydrocarbons and are not changed physically or chemically during the removal of gasoline so that they may themselves be recovered and used again and again.

Referring to the schematic layout of Fig. 1, it may be supposed that the products of combustion from the internal combustion engines employed in an oil field are collected in a suitable reservoir *a* from which they may be led either directly through a pipe *a'* or through a compressor *a*² by pipes

*a*³, *a*⁴ to a pressure well *b* having a gas-tight head *b'*. The products of combustion are introduced through this pressure well to the oil bearing stratum *c* and force the oil therein to some extent, but more particularly the volatile gas formed by evaporation above the oil, to the venting well *d* from which the pressure medium with the recovered vapors may be withdrawn by a gas pump *e*. Where, as is contemplated, the gasoline is to be removed from the recovered products, by the first proposed method, the gasoline is absorbed from the recovered mixture. A plant for removing this gasoline by the absorption method is indicated as comprising a compressor *f* to which the mixture is delivered from the pump *e* and well *d* and a tank *g* to which the mixture is delivered under high pressure from the compressor. This tank is filled with a heavy oil and this oil absorbs from the mixture introduced into the tank under pressure all of the hydrocarbon products for which it has an affinity. The pressure medium comprising the products of combustion is nonabsorbable in the hydrocarbon of the stratum and in the absorbent placed in the tank *g*, so that it finally escapes through a pipe *g'* and may be led back to the tank *a* for further use. The recovered products may be withdrawn from the bottom of the tank through a vent *g*². During the process noted, the danger usually encountered is met at the compressor *f* where the recovered hydrocarbon products are compressed to a very high pressure and the compressor itself is heated to a very high temperature. Where the mixture thus compressed is explosive, the danger is very great and it is for this reason that the use of air as a pressure medium is very objectionable. The waste products of combustion derived from the tank *a* have had the free oxygen removed therefrom so that this gas is most desirable as a pressure medium since it does not form an explosive mixture with the recovered products and the mixture may safely be compressed to any degree.

A further phase of the improved method which is clearly indicated in Fig. 1 has to do with the introduction in the well head *b'* of water from a pump *h* through a pipe *h'* introduced into the mouth of the well in such relation thereto as to have an injector action during the introduction of the water. This water will pick up the products of combustion entering the well head *b'* through the pipe *a'*, whether those products be under pressure or not and during the drop of the water through the well *b* with the gas, the gas will be highly compressed and so available for work in the oil bearing stratum as a pressure medium. When the water and gas enter the pressure medium, the water being of greater density will enter

the oil and agitate it thoroughly, while the gas itself, being of lesser density, will flow along the top of the oil and pick up the volatilized vapors. The violent agitation

5 given the oil by the water will tend to facilitate evaporation, while the flow of the current of gas along the surface will further accelerate this evaporation.

10 A further feature of the invention contemplates the heating of the water introduced from the pump *h* so that when the water in intimate contact with the compressed gas reaches the bottom of the well where the gas expands, the heat required 15 by the gas for expansion is provided for by the heat carried by the water. In this way, the chilling effect of the expanding gas on the oil and gas in the sand *c* is eliminated and the oil and gas at least have their normal 20 temperatures maintained so that evaporation is not retarded by the described chilling action usually encountered.

From the description given, it will be evident that the most desirable physical conditions 25 for evaporation of the oil and gas are created by the improved method. The chilling of the expanding gas is neutralized by the heated water, the oil is agitated violently by the introduction of water into the 30 body of the oil and the gas introduced simultaneously with the water passes in a constant current along the surface of the oil, assists in the evaporation during the agitation by the water and picks up all of the 35 volatile gases to be found in pockets, crevices or the like.

The desirable conditions described in connection with the apparatus shown in Fig. 1 are all maintained in the embodiment of 40 Fig. 2, the different apparatus shown in this figure for the purpose of removing the gasolene merely emphasizing the availability of the present method for any conditions. In Fig. 2, apparatus is shown conventionally for removing gasolene by the refrigeration method. All of the elements and conditions described in connection with Fig. 1 may be employed in connection with the refrigerating apparatus of Fig. 2. The 45 recovered products pass from the venting well *d*, in part, through the gas pump *e* and from thence to the compressor *f* in much the manner described and are compressed by the compressor *f* to a very high point 50 and then forced through the refrigerating plant *G* for the condensation of the gasolene in a way which is known in the art and with the details of which the present invention is not concerned.

60 As noted above, the modified apparatus shown in Fig. 2 merely emphasizes the availability of the improved method for use under any conditions and particularly the importance of the association of a deoxidized gas with the recovered products, so that the

resulting mixture will be non-explosive and may be compressed to any point without danger.

I claim as my invention:

1. The method of recovering oil and gas 70 which consists in introducing into the oil bearing stratum under pressure a heated, deoxidized gas to mix with the hydrocarbon vapor in the oil bearing stratum, and finally recovering the hydrocarbon from the mix- 75

2. The method of recovering oil and gas which consists in introducing into the oil bearing stratum under pressure a heated nonabsorbable deoxidized gas to mix with 80 the hydrocarbon vapor in the oil bearing stratum, compressing the recovered mixture to a high pressure and recovering the hydrocarbon.

3. The method of recovering oil and gas 85 which consists in introducing into the oil bearing stratum a gas under pressure and introducing simultaneously with the gas a liquid under pressure.

4. The method of recovering oil and gas 90 which consists in introducing into the oil bearing stratum a gas under pressure and introducing simultaneously with the gas a heated liquid under pressure.

5. The method of recovering oil and gas 95 which consists in introducing into the pressure well a liquid under pressure and at the same time introducing into the well a gas, the liquid having an injector action on the gas and compressing it.

100

6. The method of recovering oil and gas which consists in introducing into the oil bearing stratum a deoxidized nonabsorbable gas under pressure and introducing simultaneously with the gas heated water 105 under pressure.

7. The method of recovering oil and gas which consists in introducing into the oil bearing stratum under pressure waste products of combustion from internal combustion 110 engines from which the oxygen has been burnt, to mix with the hydrocarbon vapor in the oil bearing stratum, compressing the mixture and recovering the hydrocarbon from the mixture.

115

8. Apparatus for recovering oil and gas comprising a source of deoxidized gas, a pump for forcing the gas into the pressure well under pressure, a compressor to receive the recovered mixture from the venting well 120 and compress it to a high pressure and means to remove the gasolene from the compressed mixture.

9. Apparatus for recovering oil and gas comprising a source of waste products of 125 combustion, a pump for forcing the products of combustion into the pressure well, a gas-tight head on the pressure well, a water pump to force water into the well head in intimate association with the gas and im- 130

press on the gas an injector action, a compressor to receive the recovered mixture from the venting well and compress it to a high pressure, an absorbing tank to receive the compressed mixture and remove the gasolene and a connection between the absorbing tank and the source of the products

of combustion to return the products of combustion from the absorbing tank after the removal of the gasolene.

This specification signed this 16th day of June, A. D. 1917.

FREDERICK SQUIRES.
